NOVELTY DOLL

Terrance R. Mitchell, 1484 W. Highway 96,
St. Paul, Minn. 55112

Filed Jan. 29, 1973, Ser. No. 327,837

Term of patent 14 years

Int. Cl. D21—01

U.S. Cl. D34—4 R

FIG. 1 is a front, perspective view showing my novelty doll design;

FIG. 2 is a front, elevation view of the novelty doll of FIG. 1;

FIG. 3 is a side, elevation view of the novelty doll of FIG. 1;

FIG. 4 is a rear, elevation view of the novelty doll of FIG. 1;

FIG. 5 is a top, plan view of the novelty doll of FIG. 1;

FIG. 6 is a bottom, plan view of the novelty doll of FIG. 1; and

FIG. 7 is a front, perspective view showing a modified version of my novelty doll design without a hat.

I claim:

The ornamental design for a novelty doll, as shown and described.
